UNITED STATES PATENT OFFICE.

ROMEO B. HAZLETT, OF PHILADELPHIA, PENNSYLVANIA, ASSIGNOR TO
CHARLES E. WILSON, OF PHILADELPHIA, PENNSYLVANIA.

ELECTRICAL COIN-INDICATING DEVICE.

SPECIFICATION forming part of Letters Patent No. 734,461, dated July 21, 1903.

Application filed January 25, 1902. Serial No. 91,173. (No model.)

To all whom it may concern:

Be it known that I, ROMEO B. HAZLETT, a citizen of the United States, residing in the city and county of Philadelphia and State 5 of Pennsylvania, have invented certain new and useful Improvements in Electrical Coin-Indicating Devices, (Case B,) whereof the following is a specification, reference being had to the accompanying drawings.

10 My invention relates to an electrical coin-indicating device by means of which the deposit of any particular coin within it is electrically indicated at a distance therefrom.

My invention is applicable to the collection 15 of tolls at a pay telephone-station; but it will be understood that its application is not thus limited, as it may be used to indicate at a distance the deposit of a particular coin for whatever purpose the collection or its indication is desired.

In general my device consists of a series of coin-pockets adapted to receive current coins 20 of the different denominations and which when any one has been filled with the coin 25 which it is adapted to receive may be so rotated or otherwise moved as to effect the making or breaking of an electric circuit, the number of such disturbances of the electrical circuit being so arranged as to indicate at 30 any point of the circuit which of the coin-pockets has moved, and consequently what coin has been deposited.

In the accompanying drawings, Figure 1 is a front elevation of my coin collecting and 35 indicating device. Fig. 2 is a longitudinal vertical section through one of the coin-pockets. Fig. 3 is a cross-section taken along the line 3 3, Fig. 1. Fig. 4 is a cross-section taken along the line 4 4, Fig. 1. Fig. 5 is a 40 partial horizontal section taken along the line 5 5, Fig. 4. Figs. 6, 7, and 8 are side elevations of the three coin-pockets, showing the disposition of the spokes thereon.

The apparatus shown in Fig. 1 is understood 45 to be inclosed in a box or other suitable receptacle for holding the money to be collected. The box should be fitted with slots capable of receiving, respectively, nickels, dimes, and quarters or other current 50 coins. Slotted coin-tubes leading from these slots are shown in the drawings, lettered, re-

spectively, A A' A². Immediately contiguous to the ends of these tubes are three corresponding rotating coin-pockets B B' B². (Shown in their upright position in Fig. 1.) 55 Each pocket is in the shape of an elongated rectangle with an interior aperture closely corresponding to the coin which it is to receive. The lower part of the rear side of each coin-pocket is enlarged at b', (see Fig. 6,) forming a counterweight. All three of the pockets are mounted alongside of each other upon the shaft F, which passes axially through the sleeve b of each, within which the shaft is free to rotate without motion of the coin-pockets, which normally remain in an upright position upon the shaft, resting at their back in stable equilibrium against a fixed cross-piece e, against which the weighted sides b' of the pockets hold them. The shaft is mounted 70 and rotates in suitable journals formed in the walls ff in the housing of the apparatus. Upon the left-hand end of the shaft is a handle. Made fast to the shaft are three disks C C C, each immediately alongside of one of 75 the rotating coin-pockets. Each disk has set in the side next the coin-pocket a pin c, which when the shaft F is in the position of the drawings prevents the possibility of the pocket being moved forward so as to rotate 80 upon the shaft. Slots d are cut through the shaft F, corresponding in position to the three coin-pockets and registering with the coin-apertures thereof when the shaft is in the position of the drawings. Each of these 85 slots takes the shape seen in Fig. 2, whereby the coin dropped into the coin-pocket, although entering the slot of the shaft, is restrained from passing completely through it by a sloping wall at one of the short ends of 90 the slot.

From a consideration of the parts which have thus far been described it will be obvious that upon manually rotating the shaft F by drawing the handle toward the operator 95 no motion will be given to any of the coin-pockets, provided no coin has been deposited therein, by reason of the stable equilibrium of the coin-pockets against the cross-piece e, the shaft F being free to rotate without disturbing them. If, however, a proper coin be deposited in one of the pockets, the coin will 100

fall until it has partially passed through the slot d of the shaft, and resting therein will form a sort of spline, which will compel that coin-pocket to rotate with the shaft, while all 5 the empty pockets will remain in their upright position.

Near the right-hand end of the shaft F the inner extremity of a coil-band spring G is made fast to it, the outer end of the spring 10 being made fast to a fixed post g . The rotation of the shaft F in the direction which has been indicated is against the torsional effect of this spring, so that if it has been thus rotated until any coin-pocket containing a coin 15 has been inverted so as to discharge its coin immediately the handle is released by the operator the shaft F , and with it the inverted coin-pocket, by reason of the engagement of pin c against its side, will return to the position shown in the drawings. Upon reaching the upright position the coin-pocket again comes to a rest against the cross-piece e and the shaft F can rotate no farther, owing to the stop-pins mentioned.

25 Each of the sleeves b has inserted in its periphery one or more projecting spokes, the number of which may preferably be arranged so as to correspond to the multiples occurring in the value of the coins which the respective 30 pockets are adapted to receive. Thus, supposing that coin-pocket B is adapted to receive a nickel, its sleeve will have one spoke inserted in it, as seen in Fig. 6. If the pocket B' is adapted to receive a dime, its sleeve should have two 35 spokes, as seen in Fig. 7. If the pocket B^2 is adapted to receive a quarter, its sleeve should have five spokes, as seen in Fig. 8. These spokes, if more than one on any one sleeve, are arranged in line around that sleeve.

40 It is, furthermore, preferable to have the spokes set so that when all the coin-pockets are resting in the same radial plane none of the spokes are in line with each other when the group is viewed axially, as seen in Fig. 45 3, but instead form a continuous and regular circumferential series. Immediately below the spoke-carrying portion of each of the sleeves b is mounted a swinging tappet J , pivoted centrally, so as to swing backward and 50 forward. The lower end of this tappet is enlarged to form a T , as seen in Fig. 3. To the forward end of the T is secured the upper end of a coiled spring j , the lower end being secured to a stationary part of the device in 55 the plane of the point at which the tappet is pivoted. By this arrangement the tappet is normally held with its upper end slightly inclined in a forward direction, as shown in Fig. 3. The upper end of the tappet is located in the path of the spokes, and as the pocket is rotated in either direction each spoke striking the end of the tappet will turn it out of its normal position sufficiently to allow the spoke to pass it, the tappet being in-

60 65 stantly returned to normal position by the spring j . In proximity to each of the tappets is a spring-contact h and an opposing contact

h' , the two contacts forming a switch in an electrical circuit $n\ n$. The spring-contact h is preferably arranged directly behind the 70 rearwardly-extending portion of the T of the tappet and sufficiently close to be actuated by the rearward movement of the lower end of the tappet to cause the circuit $n\ n$ to be closed. This movement of the tappet is 75 caused by a spoke striking the upper end of the tappet and pushing it forward as the pocket carrying the spoke is returning to normal position after being inverted to discharge the 80 coin placed in it. During the rotation of the 85 pocket in a direction to invert it the spoke or spokes carried by it striking the upper end of the tappet will cause the lower end of the tappet to move forward against the force of the spring j , this movement not affecting the 90 normal position of the spring-contact h , and consequently not closing the circuit $n\ n$. All of these switches are inserted in parallel in the same electrical circuit $n\ n$, which includes a battery and any device for indicating or 95 registering electrical impulses, whether bell, ticker, or register, situated at the point where the indications are to be received.

The operation of the parts thus far described is as follows: Until a coin has been 95 deposited in one of the pockets rotation of the shaft will have no effect upon them and none of the electrical switches can be closed so as to make a circuit. Whenever a coin has been inserted in any one of the pockets, 100 that pocket will be inverted by rotation of the shaft and when the shaft is released returned to its former position, as has been explained. By the motion of inversion the coin is dropped into the box, but no closing 105 of the electrical circuit will occur. During the return of the pocket to its upright position the spoke or spokes attached to it will close the electrical circuit a corresponding 110 number of times, indicating how many multiples of five cents are represented by the coin deposited. Furthermore, if two coins be deposited at once—say, for instance, a dime 115 and a quarter—the same result will be obtained, for there will then be seven closings of the circuit, indicating the deposit of thirty-five cents.

In order to prevent possible tampering with the device by improperly moving the handle backward and forward short distances, causing a repetition of the contacts without the deposit of a coin, I have provided the devices illustrated especially in Figs. 4 and 5, which only allow rotation in one direction until a complete semirevolution 125 has been effected, whereupon rotation is only allowed in the other direction until the shaft is returned to the initial position. To this end an escapement-wheel M is made fast to the shaft, which wheel is made subject to 130 regulation in three respects, as follows:

An ordinary escapement-anchor l is pivoted in such relation to the escapement-wheel as to control its motion. The lower edge of

- the escapement-anchor carries an arm l' with a weight l^2 on the end thereof. The escapement thus provided prevents rapid rotation of the shaft in either direction, and, further-
 5 more, the vibration of the weight l^2 , which is thereby occasioned, is useful as occasioning a jarring of the apparatus during the rotation of the shaft, which prevents the accidental sticking of the coin within the pocket.
 10 In front of the escapement-wheel M is mounted a spring-detent m , having a detaining-point m' and also alongside thereof an upward extension m^2 . This detent prevents rotation of the shaft F in the direction occasioned by drawing the handle forward unless the detent is pressed back out of reach of the teeth of the escapement-wheel by means of swinging arm P coming into contact with its upward extension m^2 .
 15 At the back of the escapement-wheel M is mounted a spring-detent n , having a detaining-point n' , and also alongside thereof an upward extension n^2 . This detent prevents rotation of the shaft F in the direction occasioned by the opposite motion of the handle unless the detent is pressed back out of reach of the teeth of the escapement-wheel by means of swinging arm Q coming into contact with its upward extension n^2 .
 20 P and Q are arms swinging freely upon the shaft, one on each side of the escapement-wheel. On the side facing arm P two pins p p' are inserted in the side of the escapement-wheel, and likewise on the side facing arm Q two pins q q' are inserted in the escapement-wheel. The operation of these two detents is as follows: In the position of the drawings it will be seen that the front detent m is pressed away from the escapement-wheel, so that the latter in rotating will clear it by the swinging arm P , which is in a horizontal position, so as to engage the extension m^2 . The swinging arm Q is hanging freely below the shaft, so that the detent
 25 n is in engagement with the teeth of the escapement-wheel. Under these circumstances the shaft can only rotate in the direction occasioned by drawing the handle toward the operator, any reversal of the motion being prevented by detent n . This condition continues until a half-revolution is completed, whereupon swinging arm Q , which has been picked up by the pin q during the rotation of the wheel M , is brought into contact with the extension n^2 of the detent n , freeing it from engagement with the escapement-wheel. At the same moment, however, detent n is placed in engagement with it by reason of the depression of arm P by contact with pin
 30 p' . Immediately, therefore, further rotation of the shaft in the same direction is prevented by detent m . Rotation of the shaft in the opposite direction, however, is permitted, and this permission continues until a half-revolution has again been completed, whereupon pin p again picks up arm P and pushes detent m out of engagement with the
 35 escapement-wheel and simultaneously pin q' pushes arm Q out of engagement with detent n , restoring the parts to the position of Fig. 4.
- Having thus described my invention, I claim—
1. In a coin-indicating device, the combination of a coin-pocket; a horizontal shaft supporting the coin-pocket and normally rotating freely therein; means for rotating the shaft; a stop preventing movement of the pocket in one direction; a counterweight carried by the pocket arranged to hold the pocket normally against the stop, thus preventing movement of the pocket in the other direction and maintaining the pocket in a position of stable equilibrium upon the shaft; and a slot through the shaft registering with the coin-aperture of the coin-pocket; substantially as described. 75
  2. In a coin-indicating device, the combination of a coin-pocket; a horizontal shaft rotating freely therein; a stop preventing movement of the pocket in one direction; a counterweight carried by the pocket arranged to hold the pocket normally against the stop in a position of upright stable equilibrium upon the shaft; a slot through the shaft registering with the coin-aperture of the coin-pocket; a disk fast upon the shaft immediately alongside of the coin-pocket; and a pin set in the side of the disk next to the coin-pocket, whereby a pocket which has been inverted by insertion of a coin may be restored to its upright position after the coin has been discharged, substantially as described. 90
  3. In a coin-indicating device, the combination of a coin-pocket; a shaft rotating freely therewith; a stop preventing movement of the pocket in one direction; a counterweight carried by the pocket arranged to hold the pocket normally against the stop in a position of upright stable equilibrium upon the shaft; means whereby upon the insertion of a coin therein said pocket is caused to rotate with the shaft; a spoke projecting from said coin-pocket; a tappet pivoted to the end of the spoke as it rotates with the coin-pocket; a spring for returning the tappet to normal position; an electrical switch in position to be operated by the other end of the tappet, whereby the switch is closed by rotation of the spoke in one direction but unaffected by rotation of it in the other direction, substantially as described. 105
  4. In a coin-indicating device, the combination of a rotatable shaft; a series of coin-pockets adapted to receive different coins, so mounted on the shaft that the shaft is free to rotate without rotating the pockets; means for normally maintaining each of the coin-pockets in a position of stable equilibrium irrespective of the rotation of the shaft; means whereby upon the insertion of the proper coin each pocket is so connected with the shaft. 115
  5. In a coin-indicating device, the combination of a rotatable shaft; a series of coin-pockets adapted to receive different coins, so mounted on the shaft that the shaft is free to rotate without rotating the pockets; means for normally maintaining each of the coin-pockets in a position of stable equilibrium irrespective of the rotation of the shaft; means whereby upon the insertion of the proper coin each pocket is so connected with the shaft. 120
  6. In a coin-indicating device, the combination of a rotatable shaft; a series of coin-pockets adapted to receive different coins, so mounted on the shaft that the shaft is free to rotate without rotating the pockets; means for normally maintaining each of the coin-pockets in a position of stable equilibrium irrespective of the rotation of the shaft; means whereby upon the insertion of the proper coin each pocket is so connected with the shaft. 125
  7. In a coin-indicating device, the combination of a rotatable shaft; a series of coin-pockets adapted to receive different coins, so mounted on the shaft that the shaft is free to rotate without rotating the pockets; means for normally maintaining each of the coin-pockets in a position of stable equilibrium irrespective of the rotation of the shaft; means whereby upon the insertion of the proper coin each pocket is so connected with the shaft. 130

that it will be rotated therewith; projections from said coin-pockets varying in number according to the denomination of the coin for which the pocket is adapted, the projections of any one pocket being arranged in line around the shaft upon which the pocket is mounted; electric spring-switches in parallel, one for each line of projections; and connections whereby upon rotation of any one of the coin-pockets its corresponding electrical switch is closed as many times as it carries projections; substantially as described.

5. In a coin-indicating device, the combination of a rotatable shaft; a series of coin-pockets adapted to receive different coins, so mounted on the shaft that the shaft is free to rotate without rotating the pocket; means for normally maintaining each of the coin-pockets in position of stable equilibrium irrespective of the rotation of the shaft; means whereby upon the insertion of the proper coin each pocket is so connected with the shaft that it will be rotated therewith; projections from said coin-pockets varying in number according to the denomination of the coin for which the pocket is adapted, the projections of any one pocket being arranged in line around the shaft upon which the pocket is mounted, but none of said projections on the different pockets being in line with each other when the group is viewed actually; electrical

spring-switches in parallel, one for each line of projections; and connections whereby upon rotation of any one of the coin-pockets the corresponding electrical switch is closed as many times as it carries projections; substantially as described.

6. In a coin-indicating device, the combination of a rotatable shaft; a coin-pocket; means whereby upon the insertion of the proper coin within said pocket it is moved by the rotation of the shaft; an electrical switch which is closed by the motion of the coin-pocket; a toothed wheel fast to said shaft; two oppositely-directed spring-pressed detents engaging the teeth of said wheel; the detents having portions thereof extending on opposite sides respectively of the toothed wheel; swinging arms mounted on the shaft, one on either side of the toothed wheel, which when directed toward the detent hold it out of engagement with the wheel; and stops on the sides of the wheel, whereby at the end of each half-revolution of the wheel one detent is placed in engagement with its teeth and the other thrown out of engagement, or vice versa, substantially as described.
